UNITED STATES PATENT OFFICE.

JOHN B. DUANE, OF SCHENECTADY, NEW YORK.

IMPROVEMENT IN SEEDING-MACHINES.

Specification forming part of Letters Patent No. 23,558, dated April 12, 1859.

To all whom it may concern:

Be it known that I, J. B. DUANE, of Schenectady, in the county of Schenectady and State of New York, have invented a new and Improved Broadcast-Seeding Machine; and I do hereby declare that the following is a full, clear, and exact description of the same, reference being had to the annexed drawings, making a part of this specification, in which—

Figure 1 is a side sectional view of my invention, taken in the line $x x$, Fig. 2. Fig. 2 is a plan or top view of the same. Fig. 3 is a detached longitudinal sectional view of a portion of the seed-box and seed-distributing device, taken in the line $y y$, Fig. 2. Fig. 4 is a detached plan or top view of a portion of the adjustable perforated slide. Fig. 5 is a detached transverse section of the covering device.

Similar letters of reference indicate corresponding parts in the several figures.

To enable those skilled in the art to fully understand and construct my invention, I will proceed to describe it.

A represents a horizontal rectangular frame, in the front part of which two transverse bars, $a a$, are secured. In the bars $a a$ teeth B are fitted. These teeth have curved shanks or standards b, double-edged, or sharp both at their front and back edges, and the teeth or shares are of triangular or lozenge shape. The shanks or standards b are fitted into the bars $a a$ either by keys or otherwise, so that they may be readily removed from and fastened thereto, and the teeth reversed, as occasion may require. This will hereinafter be more particularly referred to. The draft-pole C is attached to the bars $a a$ at their center.

D is a seed-box, which extends entirely across the machine and is attached to uprights c c, so that it will be a short distance above the frame A. The bottom d of the seed-box is stationary, and has oblong perforations e made in it at equal distances apart, said perforations being almond-shaped, or of greater width one end than at the other, with rounded or semicircular ends. (See more particularly Fig. 4.)

Directly over or on the perforated bottom d of the seed-box D an adjustable slide, f, is placed. This slide f is perforated with holes g of precisely the same shape as the perforations e. The perforations g, however, are in a reverse position to the perforations e. The

slide f is allowed to be moved or adjusted longitudinally in the seed-box, and is retained at any desired point by a slide, h, at one end of the seed-box, which slide fits into a rack, i, on the slide f. (See Fig. 3.)

In the seed-box D, above the slide f, a reciprocating bar, E, is placed and fitted in guides or bearings i' i'. The under side of the bar E has pendent rods j attached to it, which extend down nearly to the slide f. (See Figs. 1 and 3.)

Below the seed-box D a roller, F, is placed. This roller extends the whole length of the seed-box, and it is grooved circumferentially, as shown at k. The grooves are placed at equal distances apart, and they coincide or register with the perforations e in the bottom d of the seed-box, as shown clearly in Fig. 3.

G is an inclined board, which is suspended by chains l below the roller F, and kept at the proper degree of inclination by a chain, l'. (See Fig. 1.) This board has a series of pins or rods, m, projecting from its face sides at right angles, said pins or rods being placed in parallel rows, the pins of one row being in line with the centers of the spaces between the pins or rods of the adjoining rows.

To the upper or elevated edge of the board G a rod or arm, n, is attached, the upper end of said arm being fitted in an oblong slot, o, in the outer end of a lever, H, which is attached by a fulcrum-pin, p, to the front side of the seed-box D. The back end of the lever H is attached to the bar E in consequence of being fitted on a vertical pin, q, attached thereto. (See Fig. 1.)

In the frame A, and back of the seed-box D and inclined board G, two parallel transverse bars, r r, are secured. In these bars are placed inclined rods or teeth s, said teeth inclining backward or toward the back end of the machine from their upper ends, as shown clearly in Fig. 1. There may be one or more rows of teeth s in each bar r, and the teeth of one bar may be in line with the centers of the spaces between the teeth of the other. (See Fig. 2.) The bars r may be permanently attached to the frame A, or they may be formed in sections and connected by joints t to the frame, and acted upon by springs u, (see Fig. 5,) in order that the teeth may to a certain extent yield or give as the machine is drawn along.

H is a roller, which is at the back part of

the frame A, and has its journals fitted to the outer ends of the lower parts of bent levers I I, which are attached one to each side of the frame A by bolts or pins *v*, said pins passing through the angles of the levers I I. To the upper parts of the levers I I bars J J are attached, one to each, the upper ends of said bars being attached to bars K, the front ends of which are attached to the upper parts of bars L L, the lower parts of which are secured to the front part of the frame A, one at each side. To the lower parts of the bars L L castor-wheels M are attached, one to each, said wheels being attached to projecting ends *w* of the bars, as shown clearly in Fig. 1. The upper ends of the bars J J are connected by a traverse-bar, *a* ^x, and a chain, *b* ^x, is attached to the center of bar *a* ^x, and to a bar, N, which is attached to the bars *r r*, or to other central parts of the frame. On the bar N a driver's seat, O, is placed, so arranged that it may slide thereon and be adjusted to balance the machine, the adjustment of the seat compensating for the varying weights of different drivers.

P is an oblong box, which is placed in the back part of the frame A, just in front of the roller H. This box has a perforated bottom, and may be divided longitudinally into two or more compartments. One end of the box is supported by a spring, Q, and the opposite end is suspended to a hook, *c* ^x.

R is a pulley, the axis of which is the bolt or pin that attaches the right-hand lever I to the frame A. This pulley is allowed to rotate freely on its axis, and it is driven by a belt or cord, *d* ^x, from the roller H, said cord passing around a smaller pulley, *e* ^x, attached to the outer side of pulley R, and concentrically with it. The pulley R has pins *f* ^x projecting horizontally from its face side, and the pulley R, by means of a belt or cord, *g* ^x, communicates motion to the roller F, said roller having a pulley, S, on it, one side of which is also provided with horizontal projecting teeth *h* ^x. (See Figs. 1 and 2.) To the frame A, and opposite one end of the board G, a spring, *i* ^x, is attached.

The operation is as follows: As the machine is drawn along the teeth B furrow the ground, the teeth (if the ground be light and friable) being adjusted so that the concave edges of the shanks *b* will face outward. If the ground be rather hard and soddy, the teeth are reversed, so that the sods will not be torn up, but divided or cut by the action of the shanks. The board G is vibrated by the teeth *h* ^x on the pulley S, said teeth acting against a beveled projection on the board, and the spring *i* ^x and

the said board, through the medium of the lever H, communicate a vibratory or reciprocating motion to the bar E. The seed in box D is kept in a loose state by the movement of the teeth *j*, and by being agitated by said teeth passes down through the perforations *g e* of the slide *f* and bottom *d* into the grooves, the discharge-passages being regulated as regards size by adjusting the slide *f* of the roller F, said roller throwing the seed on the inclined toothed board G, which distributes the seed evenly and in a broadcast manner on the ground. The teeth *s* harrow the seed into the ground or cover the same, said teeth being inclined, as previously described, so as to avoid throwing up sods or lumps and to pulverize the latter and to pass over the former. The box P has a reciprocating movement given it by the teeth or pins *f* ^x on the pulley R, said pins acting against a beveled end of the box and the teeth spring Q, and from this box P small seed, grass-seed, or any suitable fertilizer may be distributed, or both may be distributed simultaneously, the seed being in one compartment and the fertilizer in the other. The roller H presses the earth on the seed. The driver from the seat O may elevate the frame A, and consequently the teeth B and *s*, by drawing down the bars J J and securing them at the desired point by the chain *b* ^x, and by fully depressing the bars J J the teeth B *s* will be elevated entirely free from the ground, so that the implement may be allowed to pass freely over obstructions and also drawn from place to place. This elevating of the frame A by the depressing of the bars J J is due to the attachment of the roller H to the bars J by the bent levers I I, and to the attachment of the castor-wheels M to the projecting ends *u* of the bars L.

What I claim as new, and desire to secure by Letters Patent, is—

1. The arrangement of the vibrating toothed board G and agitating-bar E, connected by the lever H, in connection with the adjustable slide *f*, and perforated bottom *d*, and grooved roller F, the whole being arranged to operate as and for the purpose set forth.

2. The roller H, when attached to the frame A by the bent levers I I and connected with the castor-wheels M through the medium of the bars J J K K L L, arranged substantially as shown, for the purpose set forth.

JOHN B. DUANE.
